[57] CLAIM

The ornamental design for a flexible lantern, as shown and described.

DESCRIPTION

FIG. 1 is a perspective view taken from the top, right side and rear of a flexible lantern illustrating our new design;
FIG. 2 is a left side elevational view thereof;
FIG. 3 is a right side elevational view thereof;
FIG. 4 is a top plan view thereof;
FIG. 5 is a bottom plan view thereof;
FIG. 6 is a rear elevational view thereof;
FIG. 7 is a front elevational view thereof; and,
FIG. 8 is a perspective view taken from the front, top and right side of our design illustrating the light portion of the lantern separated from the base portion of the lantern.
